(57) CLAIM

I claim the ornamental design for a swimsuit, as shown and described.

DESCRIPTION

FIG. 1 is a perspective view of the present invention showing the invention as it would be seen on a woman;

FIG. 2 is a front view of the present invention;

FIG. 3 is a back view of the present invention;

FIG. 4 is a first side view of the present invention; and,

FIG. 5 is an opposite side view of the present invention.

The broken lines formed by linear segments of equal length are provided for environment only and form no part of the claimed design.
